UNITED STATES PATENT OFFICE

CHARLES B. PAGE AND WARREN DEAN BURTON, OF EVANSTON, ILLINOIS, ASSIGNEES
TO GEORGE W. DULANY, JR., OF CHICAGO, ILLINOIS

STEAM-CONDENSING APPARATUS

Application filed June 23, 1926. Serial No. 117,912.

This invention relates particularly to apparatus for condensing steam exhausted from a turbine or engine employed to drive a locomotive or a railway car.

5 Among the salient objects of the invention are to provide improved means for supplying air to the radiators in which the steam is condensed, and to provide thermostatically-controlled means for varying the supply of air 10 as required to effect condensation of the steam.

In the accompanying drawings.

Figure 1 is a transverse vertical sectional view of a railway car embodying the features of our invention.

15 Fig. 2 is a fragmental longitudinal view of the upper portion of the car.

Fig. 3 is a fragmental transverse sectional view of one of the radiators and the shutters therefor, illustrating diagrammatically a thermostatically-controlled means for operating the shutters.

Fig. 4 is a detail side view of one of the radiators.

20 By way of example, the car is shown as provided with a steam turbine 1 which supplies power for driving the car. The exhaust steam may be conducted from the turbine to the condensing apparatus by any preferred arrangement of conduits and pipes. Herein we have shown two main conduits 2 extending from the turbine to two conduits 3 extending longitudinally of the car below and near the vertical plane of the 25 side walls. In each of the conduits 3 is a spray pipe 3^a by means of which water is sprayed upon the steam to promote condensation. Each of the conduits 3 is connected by means of a suitable number of pipes 4 to a series of radiators 5 forming the sides of 30 the clearstory 6 of the car.

40 The radiators 5 may be of any preferred or well-known character. We have herein shown a form of construction comprising a top header 7, a bottom header 8, and a riser 9 at one end of the radiator, the upper end of said riser being connected to the header 7. The pipe 4 discharges steam into the lower portion of the riser 9, as indicated by arrows in Fig. 4. A spray pipe 10 extends

longitudinally of and within the top header 7 and is provided with jet openings whereby water is sprinkled upon the steam contained in the radiator. The spray water and the water of condensation is drained from the bottom header 8 through a pipe 11 which extends to a sump 12 (Fig. 1), whence it is withdrawn by means of a pump 12^a as required for the generation of steam and for supplying water to the spray pipes 3^a and 10. 55

60 13 are drain pipes connecting the conduits 3 with the sump 12.

The condensate pump 12^a may be a so-called wet vacuum pump which serves to withdraw water and any air contained in the system, but if desired, a separate air pump or air ejector may be used.

Means is provided for drawing air through the radiators 5, said means being herein shown as comprising an exhauster located 70 between each pair of radiators arranged at opposite sides of the clearstory. In the drawings, the numeral 14 denotes an exhauster unit of known construction comprising a fan 14^a arranged to revolve in a horizontal plane 75 and to discharge air upwardly.

The series of exhausters 14 may be driven in any preferred manner. Herein we have indicated that the exhausters are driven from a shaft 15 extending longitudinally of and within the clearstory 6. The shaft 15 may be driven from any suitable source, as, for example, an auxiliary turbine driven by a portion of the exhaust from the main turbine 1, as explained in our application Serial No. 62,062, filed October 12, 1925. When thus driven, the exhaust fans are operated at a speed proportionate to the quantity of exhaust steam to be condensed.

Weather conditions or other factors may 90 make it desirable to control the supply of air to the radiators 5. We therefore provide for each radiator a series of shutters 16 arranged at the outer side of the radiator, each shutter being pivoted at 17 and arranged to swing 95 into and out of a position which substantially prevents the entrance of air through the radiator. Any desired means may be provided for automatically moving the shutters 16 in accordance with changes in temperature 100

of the water in the lower header 8. Herein we have indicated a cylinder 18 (Fig. 3) containing a piston 19 which is connected by means of a rod 20 and linkage 21 to the shutters 16. A coiled expansive spring 22 tends to move the piston 19 downwardly to close the shutter. The space within the cylinder 18 below the piston 19 is connected by means of a tube 23 to a closed container 24 located within the lower header 8, said container, the tube 23 and the space within the cylinder 18 below the piston 19 being filled with a fluid, the expansion and contraction of which as the temperature of the condensate changes resulting in corresponding movement of the piston 19 and hence of the shutters 16.

The location of the fans between the radiators 5 and discharging directly to the atmosphere is advantageous in that there is no back pressure on the fans except that of the atmosphere. Moreover, when the shutters 16 are in closed or nearly closed position, there is little or no air flowing through the radiators, and the load on the fans is correspondingly light, with consequent saving in power.

We claim as our invention:

1. In railway rolling stock, a body having a clearstory, series of radiators forming the sides of the clearstory, an exhauster unit located in the clearstory between each pair of oppositely arranged radiators, each such unit being arranged to discharge air upwardly directly into the atmosphere and draw air into the clearstory through the radiators, shutters at the outer sides of the radiators, thermostatically-controlled means for adjusting the shutters, said thermostatically-controlled means being responsive to temperature changes in the water in the lower portion of the radiators, and means for discharging exhaust steam into the radiators.

2. In railway rolling stock, two radiators arranged opposite each other in generally parallel relation, an exhaust fan located between the radiators and arranged to discharge air upwardly directly into the atmosphere and draw air through the radiators, shutters at the outer sides of the radiators, thermostatically-controlled means for adjusting the shutters, said thermostatically-controlled means being responsive to temperature changes in the water in the lower portion of the radiators, and means for discharging exhaust steam into the radiators.

3. In railway rolling stock, a body having a clearstory, series of radiators forming the sides of the clearstory, an exhauster unit located in the clearstory between each pair of oppositely arranged radiators, each such unit being arranged to discharge air upwardly directly into the atmosphere and draw air into the clearstory through the radiators.

4. In railway rolling stock, two radiators arranged opposite each other in generally parallel relation, an exhauster unit located

between the radiators, and arranged to discharge air upwardly directly into the atmosphere and draw air through the radiators, and thermostatically controlled means responsive to temperature changes in the radiators to adjust the flow of air through said radiators.

5. In railway rolling stock, a steam prime mover, a body, a plurality of radiators located at the upper portion of the body, an exhaust conduit extending longitudinally of the body at the lower portion thereof and connected to the prime mover, pipes connecting said conduit to the radiators, and a spray pipe extending longitudinally of and within said conduit.

6. In railway rolling stock, a body having two radiators arranged opposite each other in generally parallel relation at the top of said body, an exhauster unit located between said radiators for causing the flow of air through said radiators, and adjustable means for controlling the flow of air through said radiators.

7. In railway rolling stock, two radiators arranged opposite each other in generally parallel relation, an exhauster unit located between said radiators for causing the flow of air therethrough, and a thermostatically controlled means responsive to temperature changes in the radiators to adjust the flow of air through said radiators.

8. In railway rolling stock, a body having a clearstory, a plurality of radiators disposed at the sides of said clearstory, an exhauster unit located in said clearstory between said opposed radiators, a prime mover, an exhaust conduit connected to said prime mover, pipes connecting said conduit to said radiators, spray means extending longitudinally of and within said conduit, spray means extending longitudinally of and within the upper portions of said radiators, and means for supplying liquid to said spray means.

In testimony whereof we have hereunto affixed our signatures.

CHARLES B. PAGE.
WARREN DEAN BURTON.
